UNITED STATES PATENT OFFICE.

GEORGE KEITH, OF LONDON, ENGLAND, ASSIGNOR OF ONE-HALF TO JAMES KEITH,
OF LONDON, ENGLAND.

APPARATUS FOR DELIVERY OF GAS AND AIR TO FURNACES.

1,363,513.

Specification of Letters Patent. Patented Dec. 28, 1920.

Application filed October 14, 1918. Serial No. 258,064.

To all whom it may concern:

Be it known that I, GEORGE KEITH, a subject of the King of the United Kingdom of Great Britain and Ireland, and residing at 5 London, England, have invented a certain new and useful Improvement in Apparatus for Delivery of Gas and Air to Furnaces, of which the following is a specification.

This invention relates to apparatus for 10 maintaining proportional delivery of gas and air supplied through separate passages to gas-fired furnaces notwithstanding variations in the resistances to the flow of these fluids or in their relative pressures.

15 An apparatus according to the invention consists essentially of two movable members, such as diaphragms, for example, said diaphragms being operatively connected to each other and to an admission valve for the 20 combustible fluid, one pair of the opposing sides of said diaphragms being influenced by pressure differences set up by the flow of the combustible fluid, and the other pair of opposing sides of said diaphragms being influenced 25 by the pressure differences across a manually adjustable member presenting a resistance to the flow of combustible fluid whereby the diaphragms are balanced.

In the accompanying drawings, Figure 1 30 represents diagrammatically one arrangement according to the invention. Fig. 2 represents a modification.

In the construction shown in Fig. 1 there are connected to the furnace A separate 35 pipes B and C, hereinafter designated, respectively, the air pipe and the gas pipe, for admission of air and gas.

The portion of the air pipe B next the furnace A may be heated by the waste products 40 of combustion from the furnace, being formed, for example, as a coil as shown at B'. At a point in the air pipe B in advance of the zone where the air is heated a choke bore D is introduced.

45 Fitted to the gas pipe C is a governor provided with two connected diaphragms E, F.

The diaphragms E, F, which are connected by a rod K, are disposed one on each 50 side of the gas inlet C' to which is fitted the butterfly valve L, and a partition N through which the rod K passes is interposed between the diaphragms E, F so as to divide

the diaphragm chamber into compartments to one of which is fitted the gas inlet 55 connection C' and to the other of which is fitted the gas pipe C leading to the furnace, the passage of gas between the compartments being controlled by a regulating valve H constituting a manually adjustable 60 resistance. Any small leakage around the rod K where it passes between the compartments does not affect the proportions as it joins in with the main quantity passing the 65 valve H.

From the high pressure side of the air pipe B, *i. e.*, from the side of the choke bore D remote from the furnace A a connection e is taken to the back of the diaphragm E on the inner face of which diaphragm E 70 presses the gas admitted by the valve L into the first compartment, and from the low pressure side of the air pipe B, *i. e.*, from the side of the choke bore D nearest the furnace A a connection f is taken to the back 75 of the diaphragm F to the inner face of which latter is transmitted the pressure prevailing in the pipe C.

A control valve J fitted to the air pipe B in advance of the choke bore D (*i. e.*, more 80 remote from the furnace A than the choke bore D) serves to regulate the quantity of air supplied.

It will be seen that with the arrangement described change of pressure in the gas pipe 85 C beyond the valve H, that is, at the side of the valve H nearest the furnace, will make itself felt on that face of the diaphragm F nearest the partition N, the combined effect of which and of the influence on 90 the gas pressure set up by the governor on the other side of the valve H in consequence of the difference of pressure prevailing on the two sides of the choke bore is to maintain across the valve H a difference of pressure 95 equal or proportionate to the difference of pressure across the choke bore D. It follows that the proportions of gas and air admitted to the furnace will be maintained constant notwithstanding variation of the resistance in either pipe or in the furnace or of other conditions which would ordinarily result in fluctuation of the proportions.

It will be seen that in the construction shown in Fig. 1 the static pressure of the 105 air on one side of either diaphragm may be

quite high compared with the static pressure of the gas on the other side of the same diaphragm.

The modified construction shown in Fig. 2 is devised so as to avoid the establishment of an excessive difference of pressures on the two sides of either diaphragm, both sides of the diaphragm E' being exposed to air pressure and both sides of the diaphragm F' being exposed to gas pressure. With the rearrangement of the tubular connections e' and f' as shown in Fig. 2 the static pressure of the air may be as high as required: but the difference of pressures on the two sides of the diaphragm E' will only be equal to the difference of the pressure on the one side and the pressure at the throat of the choke bore D' or its equivalent. In this arrangement also change of pressure in the gas pipe C beyond the valve H will make itself felt on the face of the diaphragm F' nearest the partition N', any rise of pressure in the pipe C being added to the pressure set up by the governor.

In practice, it is found that the sensitivity of the apparatus is much improved when the stroke of the diaphragm is kept as short as possible, so as to reduce any stretching effect on the diaphragms or excessive puckering in the transition from one extreme position to the other.

To attain this desirable result, the modified governor valve arrangement shown in Fig. 2 may be adopted, the arrangement including a relay so that the governor valve may be operated with minimum force.

As shown, the governor valve consists of a diaphragm valve L' which is adapted to bear on a valve seating L², and at the back of which is a diaphragm chamber L³ into which is a small leak L⁴ from the gas supply admitted through the pipe connection C'.

Centrally of the diaphragm L' is a small relay valve L⁵ operable directly by the governor diaphragms E', F' through the rod L⁶.

It will be evident that, as soon as the opening of the relay valve L⁵ permits the pressure on the back of the diaphragm L' to fall by permitting the passage of a quantity of gas in excess of what can pass through the leak L⁴, the pressure of the gas acting on the exposed annular surface of the diaphragm will open the valve L', and that, conversely, when the relay valve L⁵ closes, the gas passing through the leak L⁴ will exercise pressure on the back of the diaphragm valve L' so as to close the latter. That is, the movement of the diaphragm valve L' simply follows the movement of the relay valve L⁵.

The contraction at D' of the passage through the pipe B' may be in effect a venturi arrangement.

In the construction shown in Fig. 2 the connection e' is taken from a point on the high pressure side of the contraction and the

connection f' taken from the throat, the end of the connection e' which enters the air pipe B being turned to face the stream and the end of the connection f' being substantially parallel to the direction of flow.

It will be understood that the arrangements described are applicable whether the gas and air be delivered under pressure or be drawn in by the suction effect of the flue or otherwise.

For the purpose of the foregoing explanation it is assumed that the fluids to be handled are gas and air. By the term "gas" it is intended to include also hydrocarbon and other combustible vapors; oxygen may also be utilized as a supporter of combustion.

What I claim is:—

1. Apparatus for maintaining the proportional delivery of a combustible fluid and a comburent fluid supplied to a gas-fired furnace, consisting of the combination of two movable members in separate compartments, said members being operatively connected to each other, an admission valve for the combustible fluid to which valve said members are also connected, and a manually adjustable device presenting a resistance to the flow of combustible fluid, said movable members being so arranged that one pair of the opposing sides of said members will be influenced by pressure differences set up by the flow of the comburent fluid, and that the other pair of the opposing sides of said members will be influenced by the pressure differences across said resistance.

2. Apparatus for maintaining the proportional delivery of a combustible fluid and a comburent fluid supplied to a gas-fired furnace, consisting of the combination of two movable members in separate compartments, said members being operatively connected to each other, an admission valve for the combustible fluid, a relay valve to which said members are also connected, and a manually adjustable device presenting a resistance to the flow of the combustible fluid, said members being so arranged that one of said members will be influenced by pressure differences set up by the flow of the comburent fluid, and the other of said members will be influenced by the pressure differences across said resistance.

3. Apparatus for maintaining the proportional delivery of a combustible fluid and a comburent fluid supplied to a gas-fired furnace, consisting of two movable elements each having two sides subject to pressure, separate compartments in which said elements are contained, an operative connection between said elements, an admission valve for the controlled fluid operatively connected to said elements, and a manually adjustable device presenting a resistance to the flow of the controlled fluid, said movable elements being so arranged that one pair of opposing

sides of said elements will be influenced by pressure differences set up by the flow of the controlling fluid, and that the other pair of opposing sides will be influenced by the pressure differences across said resistance so that said elements are balanced.

4. Apparatus for maintaining the proportional delivery of a combustible fluid and a comburent fluid supplied to a gas-fired furnace, consisting of the combination of two diaphragms operatively connected to one another, separate compartments in which said diaphragms are contained, an admission valve for the combustible fluid, a relay valve 10 to which said diaphragms are also connect- 15

ed, an adjustable resistance to the flow of the combustible fluid, and connections from the opposite sides of one diaphragm to spaced points of the passage for the comburent fluid, the opposite sides of the other diaphragm being exposed to the pressure of the combustible fluid on opposite sides of said resistance. 20

In testimony whereof I have signed my name to this specification in the presence of 25 two subscribing witnesses.

GEORGE KEITH.
